CLAIM

The ornamental design for a stove top heating element,
as shown and described.

DESCRIPTION

FIG. 1 is a top plan view of a stove top heating element
showing my new design, the bottom view being a mirror
image;

FIG. 2 is a top and side perspective view thereof; and,
FIG. 3 is a side elevational view thereof.

The body of the heater shown in broken lines in FIGS.
1-3 is shown for illustrative purposes only and forms no
part of the claimed design.

FIG. 1

FIG. 2

FIG. 3
